UNITED STATES PATENT OFFICE.

ORIN FRED TORERON, OF ARDMORE, OKLAHOMA.

SWIMMING SHOE.

Application filed November 16, 1922. Serial No. 601,312.

To all whom it may concern:

Be it known that I, ORIN F. TORERON, a citizen of the United States, residing at Ardmore, in the county of Carter, State of Oklahoma, have invented certain new and useful Improvements in Swimming Shoes; and I do hereby declare the following to be a full, clear, and exact description of the invention, such as will enable others skilled 10 in the art to which it appertains to make and use the same.

This invention relates to new and useful improvements in swimming devices and particularly to swimming sandals.

15 One object of the invention is to provide a novel, simple, and cheap device of this character which can be comfortably worn by the swimmer, and which will be light in weight.

20 Another object is to provide a swimming sandal having feathering propelling wings which are constructed and arranged to lie normally in spread position until feathered by the upward movement of the swimmer's 25 foot.

A further object is to provide propelling wings of a swimming sandal which will automatically spread into operative position immediately prior to the power stroke of 30 the swimmer's foot, whereby the loss of power during a part of the stroke is obviated.

Other objects and advantages will be apparent from the following description when 35 taken in connection with the accompanying drawing.

In the drawing:

Figure 1 is a perspective view of a swimming sandal made in accordance with the 40 invention, the wings being in normal spread position.

Figure 2 is an enlarged side elevation of the sandal showing the wings feathered.

Figure 3 is an enlarged plan view of a 45 portion of the attachment, removed from the shoe.

Figure 4 is a section on the line 4—4 of Figure 2.

Referring particularly to the accompanying drawing; 10 represents a sandal having the sole 11, and secured at its ends to the sole is a longitudinally extending flexible plate 12. Formed in this plate, adjacent the ends thereof, are the openings 13 for the 50 reception of the tongues 14 of the propelling wings 15. Each of the wings 15 is a

half disk and extends, with its curved side toward the outside edge of the shoe sole. The inner longer edge 16, of each disk is slightly bowed outwardly and is arranged 60 to bear against the face of the plate 12, to cause a flexing of the plate, in a direction toward the sole of the sandal, when the wing is swung to extend at right angles to the sole. It will be noted that the tongues 65 of the two semi-disks are disposed in the openings 13, at the opposite ends of the plate and are so arranged therein that each wing has free pivotal or swinging movement without interference by the other 70 wing.

The flexibility of the plate 12 normally urges the wings into a plane parallel with the sole of the sandal, that is in operative position, so that when the swimmer moves 75 his foot rearwardly, in the power or propelling stroke, the wings will press against the water and propel the swimmer. When the swimmer draws his foot forwardly, the resistance of the water will cause the wings 80 to swing rearwardly on their tongues, into a position approximately parallel, and in so moving the inner curved edges 16 press against the plate 12 and flex the same, thus holding it under tension until just prior to 85 the rearward movement of the swimmer's foot in the power stroke, when the plate 12 will straighten out and swing the wings into laterally extended position to bear 90 against the water, as the foot moves rearwardly.

Ordinarily, in devices of this character, the foot of the swimmer must be moved a part of the rearward, or power stroke, before the wings spread open into propelling 95 position. With the present device the wings are spread at the first instant of the power stroke, thus increasing the power, and saving a great amount of energy.

What is claimed is:

1. The combination with a swimming sandal, of a flexible strip mounted on and extending longitudinally of the sole of the sandal, and foldable propelling wings movably mounted on the flexible strip and arranged to be moved into spread position thereby and into folded position by pressure of water.

2. The combination with a swimming sandal, of a flexible strip mounted on the sole of the sandal, and propelling wings movably mounted on the flexible strip and

having their adjacent edges engaging therewith to flex said strip upon movement into folded position and to be moved into spread position by said strip.

5. 3. The combination with a swimming sandal, of a flexible strip secured to and extending longitudinally of the sole of the sandal, the end portions of the strip being formed with openings, and a pair of wings 10 having tongues movably disposed in the openings to permit swinging movement of the wings.

4. The combination with a swimming sandal, of a flexible strip secured to the sole 15 of the sandal and provided with openings, and a pair of foldable wings having tongues movably disposed in the said openings.

5. The combination with a swimming

sandal, of a flexible strip secured to and extending longitudinally of the sole of the 20 sandal and provided with openings, and a pair of foldable wings having tongues movably disposed in the said openings, the wings being in the form of half disks, with their mutually adjacent edge portions longitudinally and outwardly curved for engagement with the flexible strip to flex the same when the said wings are in inoperative position, and to be moved into spread position by the said strip.

In testimony whereof, I affix my signature, in the presence of two witnesses.

ORIN FRED TORBRON.
